CLEANING COMPOSITION

Wesley E. Combs, Okmulgee, Okla.
No Drawing. Application July 9, 1952,
Serial No. 298,009

2 Claims. (Cl. 252—152)

The present invention relates to novel cleaning compositions for removing foreign matter on objects of various compositions such as textiles, leather, glass materials, paints, chrome, stainless steel, woodwork, etc., without in any way impairing the physical qualities of the object to be cleaned.

Objects and advantages of the invention will be set forth in part hereinafter and in part will be obvious herefrom, or may be learned by practice with the invention, the same being realized and attained by means of the compositions and combinations pointed out in the appended claims.

The invention consists in the novel compositions, combinations and improvements herein described.

An object of my invention is to provide a novel cleaning composition comprising a nicotine and water mixture, said composition having surface active and detergent properties as well as lowering the surface tension and interfacial tension between the object being cleaned and foreign matter such as dirt, grease, wax, etc., deposited on said object.

Another object of my invention is to provide a novel cleaning composition comprising nicotine, water and blue indigo, said composition not only having improved detergent and surface active properties, but also having the property of improving the lustre and color of the object being cleaned.

A still further object of my invention is to provide an improved detergent composition comprising a detergent composition, either natural or synthetic, having incorporated nicotine for improving the cleaning action of said detergent.

Another object of my invention is to provide a novel method of cleaning, using the novel compositions of the present invention.

According to one of the features of my invention, I have discovered that a composition containing water and nicotine in at least about .007% by weight of the total composition, provides a cleaning composition having unique surface active and detergent properties. The effectiveness of this composition increases with the increase of nicotine up to where the nicotine is about 33% by weight of the total composition. Cleaning compositions in the above ranges are highly desirable, for at those ranges the nicotine will volatilize into the air after application to the object to be cleaned, thus preventing the depositing of any foreign matter from the cleaning composition on the object cleaned. Above the upper limit range of 33%, the volatility of the nicotine decreases, with the result that there is a possibility of staining said object with nicotine if the concentration of nicotine in the cleaning composition is too high.

The above cleaning compositions possess excellent detergent, wetting, surface active and deflocculating properties. Furthermore, on application of said composition to an object to be cleaned, the surface and interfacial tensions between the object and foreign matter are low-

ered, thus facilitating the removal of the foreign matter from said object.

Advantageously, the above cleaning compositions have incorporated therein blue indigo in the range of about 0.0005% to about 0.50% by weight of the total composition. The addition of the blue indigo increases the cleaning properties of said compositions as well as adding a shine or lustre to the object being cleaned, and at the same time improving the color of said object.

One of the outstanding features of the novel nicotine and water mixture is that the cleaning properties of a detergent, whether natural or synthetic, are improved by the addition of nicotine to said detergent to improve its cleaning action. Preferably, the nicotine is added to the detergent in the form of a nicotine and water mixture, as defined above. If so desired, however, the nicotine may be added by itself. In either case, the detergent composition is diluted with water before it is used in cleaning. Among the natural detergents which may be improved, 15 are organic alkali metal soaps derived from the saponification of higher fatty acids by sodium and potassium hydroxide such as the soaps prepared by the saponification of tallow, palm oil, cocoanut oil and cottonseed oil with sodium hydroxide, and the saponification of linseed oil, fish oils and hemp oils by caustic potash. Natural inorganic detergents may be illustrated by soda ash, potash and caustics such as sodium hydroxide and potassium hydroxide.

Any suitable synthetic detergent composition may be used, such as the alkali salts of alkyl aryl sulfonates and sulfated alcohols, polyoxyalkylene ethers and their derivatives. Specific examples of typical synthetic detergent compositions which may be improved by the addition of nicotine are as follows, the per cents being expressed by 30 weights:

- (1) Sodium ethyl methyloleylamide sulfonate, 30%; sodium sulfate, 64%; sodium carbonate, 0.9%; sodium chloride, 4.6%; water, 0.5%.
- (2) Sodium lauryl sulfate, 38.8%; sodium carbonate, 1.3%; sodium sulfate, 57.8%; water, 2.1%.
- (3) Sodium alkyl aryl sulfonate, 33.4%; sodium carbonate, 1.6%; sodium sulfate, 62.6%; water, 2.4%.
- (4) Sodium sulfated monoglyceride, 32%; sodium carbonate, 1.3%; sodium sulfate, 64.7%; water, 2.0%.
- (5) Keryl benzene sodium sulfonate, 40%; sodium sulfate, 24%; sodium carbonate, 4.8%; trisodium phosphate, 9%; sodium silicate, 10%; sodium carboxy methyl cellulose, 0.5%; water, 11.7%.
- (6) Alkyl aryl sodium sulfonate, 37%; sodium sulfate, 9%; magnesium sulfate, 5%; disodium phosphate, 4%; sodium pyrophosphate, 33%; sodium tripoly phosphate, 3%; sodium carboxy methyl cellulose, 0.7%; water, 8.3%.
- (7) Sodium salt sulfated alcohols, 20%; sodium sulfate, 15%; sodium carbonate, 1.4%; sodium chloride, 0.5%; disodium phosphate, 6.7%; sodium pyrophosphate, 14.6%; sodium tripoly phosphate, 27.8%; sodium carboxy methyl cellulose, 0.5%; sodium silicate, 3.8%; water, 9.7%.
- (8) Polyoxyethylene ether, 20%; sodium carbonate, 21%; sodium pyrophosphate, 39%; starch, 15%; water, 5.0%.
- (9) Alkyl aryl sodium sulfonate, 25%; sodium sulfate, 17%; sodium carbonate, 1%; disodium phosphate, 2.2%; sodium tripoly phosphate, 7.5%; sodium silicate, 4.5%; sodium carboxy methyl cellulose, 0.4%; sodium pyrophosphate, 31%; water, 11.4%.
- (10) Triethanolamine lauryl sulfate, 52%; isopropanol, 24%; water, 24%.
- (11) Polyoxyethylene ether, 53%; sodium chloride, 0.4%; water, 46.6%.

(12) Polyoxyalkylene ether of partial palmitic acid ester.

(13) Modified alkyl aryl sodium sulfonate.

(14) Sodium salt of technical lauryl sulfate.

Whether the nicotine be added by itself to the detergent or in the form of a water and nicotine mixture, the detergent should contain at least .0000042 parts nicotine to one part of detergent. The maximum nicotine preferred is about .5 part of nicotine to 1 part of detergent. Hence, if the nicotine is added in the form of a nicotine and water mixture, the nicotine and water mixture, wherein the nicotine is in the range of 0.0007% to 33% by weight of the total mixture, is added to the detergent in the ratio of about .06 to 1.5 parts by weight of said mixture to about 1 part by weight of the detergent. If so desired, blue indigo may be added in the range of about .00000003 to about .0075 part per part of detergent. If a nicotine and water mixture is used, the range would be about .0005% to about .5% blue indigo of the total nicotine and water mixture.

In either case, the detergent containing nicotine, whether added by itself or in the form of a nicotine and water mixture, is diluted with from zero to 4 gallons of water (15,140) for every gram of detergent in said composition.

In order to describe the invention more specifically, the following working examples are now given.

Example I

One quarter of a gram of nicotine is added to a gallon of water and mixed thoroughly.

A sheet of glass material containing dirt, grease, and other foreign matter is then cleaned by depositing 5 grams of said above mixture on said sheet and rubbing said mixture on said sheet. This results in the removal of said foreign matter from said sheet. Any nicotine which has been inadvertently left on said sheet due to improper wiping, volatilizes from said sheet, thus leaving said sheet in a clean and yet untarnished condition.

Example II

Fifteen grams of nicotine are added to eighty grams of water and mixed thoroughly.

A strip of leather having deposited thereon dirt, wax and other foreign matter is cleaned by depositing 3 grams of said above mixture on said strip and rubbing said mixture on said strip, thus removing the foreign matter from said strip, said mixture in no way interfering with the quality of the leather strip.

Example III

One-thousandth of a gram of blue indigo is added to a nicotine and water mixture prepared under the conditions stated in the first paragraph of Example II.

A sheet of iron having a chrome finish and having deposited thereon dirt, grease, wax and other foreign matter is cleaned by depositing 3 grams of said above mixture on said sheet and rubbing said mixture on said sheet. By this application, the foreign matter is not only removed from said sheet, but also the chrome is provided with a bright shine or lustre.

Example IV

Ten grams of a nicotine and water mixture prepared under the conditions of the first paragraph of Example II are mixed with ten grams of sodium tallow soap. This mixture is then diluted with one gallon of water.

A strip of woodwork having a maple finish and having deposited thereon dirt, oil and other foreign matter is cleaned by depositing 15 grams of said above mixture on said strip and rubbing said mixture on said strip, whereby the foreign matter on said strip is removed therefrom, resulting in the strip having a new-like appearance.

A second strip, substantially the same as the first, is then cleaned by applying 15 grams of a sodium tallow soap and water mixture, prepared by adding ten grams

of said soap to one gallon of water, and rubbing said mixture on said strip. Although some of the foreign matter is removed by said application, it is not as effective a cleaning composition as the soap, nicotine and water mixture. The first strip has a much cleaner and newer appearance than the secondly cleaned strip, thus showing the superiority of the first described cleaning composition.

Example V

10 15 gram of a nicotine and water mixture prepared under the conditions of the first paragraph of Example II is mixed with ten grams of a synthetic detergent consisting by weight of 30% sodium ethyl methloleylamide sulfonate, 64% sodium sulfate, 0.9% sodium carbonate and 4.6% of sodium chloride. This mixture is then diluted with one gallon of water.

A sheet of white cotton fabric having deposited thereon dirt, grease and other foreign matter is cleaned by depositing 100 grams of said above mixture on said fabric 20 sheet and rubbing said mixture on said sheet, whereby all of the foreign matter on said strip is removed efficiently.

A second sheet of cotton fabric, substantially the same as the first, is then cleaned by applying 100 grams of water 25 and detergent mixture, prepared by adding ten grams of a detergent, having the same chemical make as the detergent defined above, to one gallon of water, and rubbing said mixture on said sheet. This mixture does not remove the foreign matter as adequately as the cleaning composition containing the nicotine and water mixture in addition to the detergent, thus indicating the superiority of the latter cleaning composition over the former.

Example VI

To a cleaning composition, prepared in accordance with the nicotine, water and tallow soap mixture of Example IV, is added one-thousandth of a gram of blue indigo.

40 A sheet of chrome metal having deposited thereon dirt, grease and other foreign matter is cleaned by depositing 5 grams of said above mixture on said sheet and rubbing said mixture on said sheet, whereby the foreign matter is removed from said sheet. The chrome metal has a bright lustre simulating that of a brand new chrome metal 45 sheet.

Example VII

To a cleaning composition, prepared in accordance with the nicotine, water and detergent mixture of Example V, is added one-thousandth of a gram of blue indigo.

A sheet of stainless steel having deposited thereon dirt, grease and other foreign matter is cleaned by depositing 5 grams of said above mixture on said sheet and rubbing said mixture on said sheet, whereby the foreign matter is removed from said sheet. As in the previous example, the stainless steel sheet has a bright lustre simulating that of a brand new stainless steel sheet.

Accordingly, the cleaning compositions of the present 60 invention are most useful and efficient. The fact that they can be used on all types of objects without impairing their physical properties makes them highly advantageous to use.

Although the nicotine and water mixtures are highly 65 desirable cleaning compositions, the incorporation of blue indigo to such compositions is recommended, for not only is the cleaning action of such compositions improved, but the object being cleaned is provided with a bright lustre and the color of the object is improved.

70 A most remarkable discovery is that the cleaning action of the conventional natural and synthetic detergents is improved by the incorporation of nicotine with the detergent, either by adding a nicotine and water mixture to the detergent, or adding the nicotine directly 75 to the detergent. In either case, the new detergent com-

positions are further diluted by adding water when used in cleaning.

The invention in its broader aspects is not limited to the specific process described but departures may be made therefrom, within the scope of the accompanying claims, without departing from the principles of the invention and without sacrificing its chief advantages.

What is claimed is:

1. A process for cleaning an object containing foreign matter deposited thereon comprising depositing on said object a composition consisting essentially of water and nicotine, the nicotine being in the range of about .007% to about 33% by weight of the total composition, and rubbing said composition on said object, whereby the foreign matter on said object is loosened and removed 10

2. A process as defined in claim 1 wherein said composition contains blue indigo in the range of about 0.0005% to about 0.5% of the total composition.
